UNITED STATES PATENT OFFICE.

ADAM HELLER, OF BALTIMORE, MARYLAND.

MOLDING-MACHINE.

1,113,626.

Specification of Letters Patent. Patented Oct. 13, 1914.

Application filed June 15, 1914. Serial No. 845,190.

To all whom it may concern:

Be it known that I, ADAM HELLER, a citizen of the United States, residing in Baltimore city and State of Maryland, have invented certain new and useful Improvements in Molding-Machines, of which the following is a specification.

This invention relates to molding machines and pertains to the class of machines 10 for molding pipe, and particularly to such machines as employ sand dropping mechanism and a sand packing roller.

The object of the invention is to provide novel and peculiar means for sifting and 15 dropping sand, and for packing sand into sand flasks.

A further object of the invention is to provide special mechanism for operating the doors of a sand box in dropping sand from 20 the box into the sand flasks.

With these and various other objects, advantages, and improved results in view, the invention comprises, essentially, a roller operated sand packer; a combined roller 25 track and swinging sand packer; means contained in the sand hopper and coöperating with a shaking screen for spreading the sand during the sifting thereof; and mechanism for controlling the doors of the sand box.

30 The roller having weights to govern the pressure on the sand packer, and the special construction of the roller, are covered by my allowed application Serial No. 666,966, in which the present application is 35 in part a divisional application, therefore the above mentioned features will not be specially claimed herein, and will only be shown and described for the purpose of carrying out this invention.

40 In the accompanying drawings forming part of this application: Figure 1 is a top view, the conveyer being partly broken away. Fig. 2 is a central vertical section showing the movement of certain parts in 45 dotted lines. Fig. 3 is a sectional elevation of part of the machine, the dotted lines showing the roller at rest. Fig. 4 is an end view showing the movement of the roller track and presser in dotted lines. Fig. 5 is 50 a detail elevation of the door locking levers. Fig. 6 is a side view of the roller partly broken away. Fig. 7 is a perspective view of one end of the combination packer and track. Fig. 8 is a perspective view of one of 55 the hopper plates. Fig. 9 is a bottom plan view of the sand box.

The same reference characters denote the same parts throughout the several views of the drawings.

The frame 1, the conveyer 2, the sand flask 3, the molding carriage 4, the sand hopper 5, the screen box 6, the sand box 7, and the shaft 8, with its connections for operating the screen or sieve, are all substantially of the ordinary type usually employed in such 60 machines. The hopper 5 is provided with stationary plates 9 having lateral projections 9^a at the top thereof, and said projections extend over the top edge of the sides of the screen-box 6, and are attached to the 65 hopper so that the box 6 may be reciprocated by the driven crank-shaft 8, in the usual manner. The plates 9 depend into the box 6, so as to leave a sand space between the side edges of the plate and the sides of 70 said box, and a sand space between the screen-sieve or mesh 10, and the bottom edge of the plates. The plates 9 are set at an angle across the hopper so as to spread or divide the sand in the screen-box into three 75 or more bodies according to the number of plates used, all of the plates direct the sand to the screen. This arrangement produces more uniform distribution of the sand to the screen, the clogging of the screen is avoided, 80 and the sand is afforded free passage to the screen.

The cut-off 11 is operated by a hand-rod 12 having a pair of levers 13 pivoted to the frame 1, and said levers are fulcrumed to the 90 cut-off by a pair of links 14. A stop-lug 15 is secured to the frame and engaged by one of said levers to limit the outward movement of the cut-off. The inward movement of the cut-off is limited by the upturned edge 16 95 of the cut-off.

The sand box 7 has a drop-door 17, the halves of which are hinged to each side of the box, and the free edges of the door overlap each other in closed position central of 100 the box. Each door is provided with a weight 18, sufficient to overcome the weight of the doors in open position, for closing them. The doors are locked in closed position by means of a pair of levers 19, pivoted to the frame 1, and connected together by a bar 20, and said levers have a notch or slot 21 in the free end thereof, and such end depends into the path of movement of a pair of keepers 22 projecting from one half of 110 the door across the other half of the door for engaging the notches 21. It is obvious

that the doors are held in closed position by the levers 19 during the filling of the sand box, and that the levers are swung out of engagement with the keepers 22 to open the doors for dropping the sand.

The means for packing the sand into the sand flask comprises a weighted roller 23, having an operating handle 23^a, and a combined packer and track for the roller. The 10 roller is hollow, and is mounted on a shaft 25, extending therethrough, and the roller has end flanges 26 of such depth as to overlap the sides of the track so as to prevent lateral movement of the roller. In order 15 to vary the weight of the roller and its pressure on the track 24, I provide the roller with weights 27, one or more of which may be hung on the shaft 25, and the roller is provided with a removable section or door 28, to permit the weights to be placed and removed as desired or as occasion may demand. Obviously the number of weights may be increased or diminished according to the pressure required on the packer.

25 The roller track 24 is formed on or attached to the top of the packer 29, by means of a central web 30 of the same width as the roller length between the roller flanges 26, so as to prevent lateral movement of 30 the roller, and said web is of sufficient depth as to elevate said flanges above the top of the packer. The under face of the packer 29 is provided with a plurality of cleats, projections or blocks 32, so arranged relative to each other and to the sand flask-openings 33, as to fit and pack the sand into said openings when the roller is operated on the track 24. A pair of levers 34 are 35 pivoted at 35 to the ends of the web 30, and also pivoted at 36 to the frame 1. The pivots 35, permit the packer to adjust itself to the flask opening 33, and the levers 34 are operated by a hand lever 34^a and a lever 35^a for raising and lowering the packer. 40 The packer is prevented from tilting outwardly when raised out of packing position, by the ends of the track engaging the edge of the levers, so that the packer is held in substantially vertical position and out of 45 interference during the operation of charging the sand flask. The packer being pivotally hung, the weight of the roller on the track will balance the packer and force it into proper packing position so as to make 50 the packer blocks 32 register with the sand filled openings 33. In order to hold the roller in position for operation I provide the frame 1, with a pair of arms 37, forming a support for the roller, and having 55 abutment ends 38. When the roller is at rest on the arms the roller handle is dropped over the abutments and prevents the roller from accidentally leaving the arms. During 60 the deposit of the sand into the sand flask, the packer is held in suspended posi-

tion, and the roller is held by the arms 37, and after such deposit, the packer is dropped into position, and the roller is rolled upon the packer track.

I do not wish to be understood as confining myself to any particular material, number, size or shape of the various parts of my invention, to any special style or form of frame, nor to any particular means for imparting motion to any of the parts of this 75 apparatus, as certain or all of such parts may be operated by suitable motive power or by hand, as may be desired.

Having thus described my invention what I claim as new and desire to secure by Letters Patent is:—

1. In a molding machine, a sand hopper, a screen box, and a plurality of diagonally arranged plates secured within the hopper and depending into the box for dividing the sand contained in the box into separate bodies.

2. In a molding machine, a sand box, sand-dropping doors hinged to the box, keepers secured to one of the doors and projecting beyond the hinged edge of the other door, and means engaging the projecting ends of the keepers for holding the doors in closed position.

3. In a molding machine, a sand-box, 95 sand-dropping doors hinged to the box, a slideable cut-off for controlling charges of sand to the box, keepers secured to one of the doors and projecting beyond the hinged edge of the other door, means engaging the 100 projecting ends of the keepers for holding the doors in closed position, and means operated by the cut-off for opening the doors.

4. In a molding machine, a sand box, 105 a pair of gravity swinging doors for opening and closing the bottom of the sand box, means for locking and releasing the doors, levers pivoted to the frame of the machine, a hand rod connecting the levers, links connecting said levers with the slide for operating the slide, and a stop on the frame 110 and engaged by the levers for limiting the outward movement of the slide.

5. In a molding machine, the combination with a flask, and a presser roller, of a 115 sand packer fitting the flask, a roller track mounted on the packer, and a pair of levers having one end pivoted to the machine frame and the other end pivoted to the packer for permitting pivot movement of the packer 120 during the swinging movement of the levers.

6. In a molding machine, a sand box, a pair of doors hinged to the bottom of the box, a weighted lever secured to each of the doors, a pair of keepers attached to one 125 of the doors and over-lapping the other door, and a pair of connected levers having a slot in the free end thereof for engaging the free end of the keepers.

7. In a molding machine, a presser roller, 130

a sand packer having a central web, a pair of levers to which the packer is pivoted for tilting movement, said levers being pivoted to the machine frame for swinging the packer, and a roller track mounted on the web.

8. In a molding machine, a supporting frame, a presser roller, a pair of arms projecting from the frame and forming a rest for the roller, a tilting and swinging packer, a roller track mounted on the packer and

carried into and out of position relative to the said rest by the swinging movement of the packer, and means for connecting the packer with the frame.

In witness whereof I hereunto set my hand in the presence of two witnesses.

ADAM HELLER.
